(57) **CLAIM**

The ornamental design of a fragrance diffuser, as shown and described.

DESCRIPTION

FIG. 1 shows a perspective view of a design of a fragrance diffuser.

FIG. 2 shows a first side view of the design.

FIG. 3 shows a second side view of the design, rotated a 1/4-turn relative to the first side view.

FIG. 4 shows a top view of the design.

FIG. 5 shows a bottom view of the design; and,
FIG. 6 shows a perspective view of the design in use with liquid in the containers.

The broken lines illustrate structure or features which form no part of the claimed design. The wood grain pattern and texture in FIGS. 1-6 and the liquid in FIG. 6 form no part of the claimed design.
